United States Patent Office.

S. F. HESS, OF ROCHESTER, NEW YORK.

Letters Patent No. 99,188, dated January 25, 1870.

IMPROVED PACKING-CASE FOR TOBACCO.

The Schedule referred to in these Letters Patent and making part of the same.

To all whom it may concern:

Be it known that I, S. F. HESS, of Rochester, in the county of Monroe, and State of New York, have invented a certain new and improved Packing-Case for Tobacco; and I do hereby declare that the following is a full, clear, and exact description thereof, reference being had to the accompanying drawings, making part of this specification, in which—

Figure 1 is an elevation of my invention, showing a segment of the tub broken away.

Figure 2 is an enlarged section of the upper end of the stave and part of the cover.

To enable others to make and use my invention, I will describe its construction.

It is well known that the present internal revenue laws require that tobacco shall be retailed from the original case or tub in which it is packed, and also that such packing shall not be used a second time for this purpose. It is found, however, that when it is packed in barrels or half barrels, as heretofore practised, much of it becomes dry, and consequently nearly or quite valueless before it can be retailed from so large a receptacle.

The object of my invention, the nature of which will be understood by reference to the specification and drawings, is to provide a small, cheap package, which can be readily opened or closed, and may be used for other purposes after the tobacco is removed.

The main portion of the case A is constructed similarly to any tub or pail, having a bottom secured in a groove near the lower edge of the staves, and the whole bound together by light iron hoops.

The cover B is let into a "rabbet," a, formed at the upper end of the staves. This "rabbet" being a little

deeper at its base, leaves a slight inward fullness near the end of the staves, as shown more clearly in fig. 2.

The edge of the cover B is somewhat concaved, as shown, to fit this projection.

The inner edge of the staves and the lower edge of the cover are slightly rounded, whereby the cover is easily entered.

When the cover is forced into the "rabbet," the staves spring outward a trifle, till the former reaches the shoulder, when the projection upon the staves springs into the concave edge of the cover, holding it securely.

By inserting a sharp instrument under or into the edge of the cover it may be easily removed.

It is evident that my invention may be used for other purposes than the one named, for which it is also valuable after the tobacco has been removed. A bale may be cheaply attached to it, as shown, which will be found convenient in many cases.

These packages can be made of a size to contain five, ten, twenty, or more pounds of tobacco, to suit the wants of the retailer.

What I claim as my invention, and desire to secure by Letters Patent, is—

As an improved article of manufacture, the tobacco-package A, provided with a detachable cover, having an "ogee" edge, and a corresponding-shaped croze in the staves, the parts all being connected as shown and for the purposes set forth.

S. F. HESS.
